Atty for W. T. Warburton

Dec. 1701

John J. Warburton, of Philadelphia, Penn.
Letters Patent No 1701 - Dated, Decr. 16. 1862

The schedule referred to in these Letters Patent and making part of the same.

To all whom it may concern,

Be it known that I, John J. Warburton of Philadelphia, County of Philadelphia, state of Pennsylvania have invented and produced a new and original design for a Military Hat; and I do hereby declare the accompanying Drawing with the following explanation of the same to form a full, clear and exact description of the said Design.

On reference to the annexed drawing

Fig. 1 represents a side view of my new design for a military hat.

Fig. 2 an end view; and

Fig. 3 a plan view.

1

Dec. 1701

The above views represent the hat as it appears when on the man's head.
 Fig. 4 represents a side view of the hat when closed, and
 Fig. 5 a vertical section on the line 1. 2. Fig. 4.

Similar letters refer to similar parts throughout the several views.

A. represents the body, B the brim, and C the crown of the hat.

The body A of the hat as seen in Fig. 2. has slightly tapering sides, and has, as seen in Fig. 1. sides still more inclined, the crown in Fig. 2 being slightly rounded, and as seen in Fig. 1. nearly semi-circular.

As seen in the plan view Fig. 3. the crown is of an oval form as is also the body from the crown to the point where it meets the rim, the latter being of an oval form, but turned up with a curve at the sides as seen in Fig. 2. and turned down with a gradual curve at the opposite ends as seen in Fig. 1.

A well defined crease D extends across the hat from the point a. Fig. 3. along the brim up the body over the crown to the point b of the crown of the hat, being deflected by the creases E which meet the crease D both in front and in the rear at the point c. Fig. 1 and 2.

Angular creases F extend from the point f in the brim (Fig. 3) to the sides of the body, at the base of the latter.

These creases represent the points where the hat has to be folded, the form of the folded hat being represented by Figs. 4 and 5.

Although I have illustrated and described certain creases and have alluded to the hat as it appears when folded up, I do not desire to make any claim either to the method of folding up the hat or to its appearance and shape when thus folded, but I limit my claim to.

The shape and configuration of the hat as represented in and by the Figures 1. 2. and 3. of the accompanying
